ADJUSTABLE FIREARM SIGHT

George F. Davis, New Haven, Conn.

Application April 2, 1947, Serial No. 738,867

14 Claims. (Cl. 33—56)

1 This invention relates to improvements in adjustable firearm sights and more particularly to a rear sight of new and improved structure particularly for use with the automatic pistols having a retractile slide upon which the sight is mounted, although this invention is not limited to such specific use.

One object of this invention is to provide a firearm sight of new and improved structure whereby it will be particularly adapted for use on a retractile firearm part.

Another object is to provide in a sight of the above nature an improved form of elevation adjusting means.

Still another object is to provide in a sight of the above nature an improved form of windage adjusting means.

A further object is to provide an improved adjustable firearm sight which will be relatively inexpensive to manufacture, simple and rugged in construction, compact, ornamental in appearance, and very efficient and durable in use.

With these and other objects in view, which will appear as the description proceeds, there has been illustrated in the accompanying drawings, a form of adjustable firearm sight in which the features and principles of this invention may be conveniently embodied in practice.

In the drawings:

Figure 1 is a side view of a firearm part with an adjustable sight having the features and principles of this invention embodied in its structure.

Figure 2 is an enlarged rear view of the sight;

Figure 3 is an enlarged top plan view of the sight;

Figure 4 is an enlarged sectional view taken on the line 4—4 of Figure 3;

Figure 5 is a sectional view taken on the line 5—5 of Figure 3;

Figure 6 is a sectional view taken on the line 6—6 of Figure 3; and

Figure 7 is a sectional view taken on the line 7—7 of Figure 3.

Referring now to the drawings wherein like reference numerals designate like parts throughout the several views, the numeral 11 denotes a firearm part, in this instance the slide of an automatic pistol which reciprocates upon the firearm at the firing of each cartridge. The firearm slide 11 is provided with a suitable transverse groove 12 in which the base 13 of the sight of this invention may be forced to rigidly secure it thereto. The undersurface 14 of the sight base 13 and the upper surface 15 of the firearm part 11 are in close engagement to insure rigidity of assembly.

The sight base 13 is of one piece of material and has a central groove 16 formed therein and which extends the length thereof whereby side flanges 17 and 18 are provided, one on each side

of the sight. A sight leaf 19 having a tongue portion 21 and a crosswise extending rear flange portion 22 is disposed with its tongue portion 21 in the groove 16 of the base 13, the tongue portion 21 being of less width than the groove 16. A transverse hinge pin 23 extends through the flanges 17 and 18 of the base 13 through the sight leaf tongue 21. The pin 23 has a head 24, which is journaled in a counterbore 22 in the base flange 18, a threaded portion 25, which is screw threaded through the leaf tongue 21, and a stem portion 26, which is journaled in the base flange 17. A coiled spring 27 reacts between the inner side of the base flange 18 and the leaf tongue 21 in a counterbore 28 provided therein to receive the spring, to maintain close contact between the cooperating threads in the leaf tongue 21 and the threaded pin portion 25.

The head 24, of the pin 23, is provided with an annular groove 29 intermediate its ends, the bottom surface of the groove 29 being formed to provide flat faces 31, in this instance four at right angles to each other so that they formed a square in cross-section. A rod 32 having an elongated shank 33, extends upwardly through a vertical opening 34 in the base flange 18, and is disposed in the groove 29 of the pin head 24. The rod shank 33 is substantially at right angles to the rod 32 and extends across the base 13 in a V groove 35 formed in the undersurface 14 of the base to receive the shank 33 and by engagement of its sides with the shank 33 to hold it firmly in place against the upper surface 15 of the firearm slide 11.

When pressed inwardly against the flat bottom surfaces 31 of the groove 29 in the pin head 24, the rod 32 acts to lock the pin 23 in place and to resist any tendency for the pin 23 to move transversely from the base flanges 17 and 18. The rod 32 also resiliently engages the flat surfaces 31 of the pin 23 at the bottom of the groove 29 in the pin head 24 to releasably retain the pin 23 from rotating. The pin head 24 is provided with a cross slot 36 by which the pin 23 may be rotated against the restraining action of the rod 32 by means of a screw driver. Rotation of the pin 23 in the proper direction will cause the leaf 19 to be adjusted transversely of the sight base 13, and the firearm slide 11, for windage adjustment of the sight (see dotted lines in Figure 7), a quarter turn of the pin 23 being indicated when as the rod 32 drops into position against the next flat surface 31 (see dotted lines in Figure 6). The opening 34 is of larger diameter than the rod 32 to allow movement thereof in the groove 29.

The rod 32 is constantly and resiliently urged into the groove 29 and against the flat surfaces 31 by a coiled spring 37 disposed in an opening 38 provided in the base flange 18. The opening 38

extends from the rear end of the base flange 18 and intersects the upper end of the opening 34 to insure that the spring 37 will freely engage the rod 32. The spring 37 reacts between the rod 32 and a plunger 39 slidably disposed in the opening 38 with its outer rounded end 41 in engagement with a lateral extension 42 of the cross flange portion 22 of the sight leaf 19. A similar plunger 43, slidably disposed in an opening 44 in the base flange 17, has its rounded end 45 resiliently forced against a lateral extension 46 of the cross flange portion 22 of the sight leaf 19 by a coiled spring 48 reacting between the plunger 43 and the flange 17 at the bottom of the opening 44. The springs 37 and 48 are so tensioned that equal pressure is maintained upon the leaf flange extensions 42 and 46 to obviate any cramping of the leaf 19 on the threaded portion 25 of the pin 23.

The plungers 39 and 43 engage the respective flange extensions 42 and 46 on surfaces 49 and 51 respectively. The surfaces 49 and 51 are in transverse alignment and extend upwardly and outwardly, in this instance rearwardly of the sight, on an angle to a vertical line at right angles to the lower surface 14 of the base 13. Acting downwardly against the rearwardly and upwardly inclined surfaces 49 and 51 the spring pressed plungers 39 and 43 constantly urge the sight leaf 19 downwardly and maintain it in any of its vertical adjustments. In this instance, the surfaces 49 and 51 are shown recessed in the leaf flange extensions 42 and 46 respectively.

The leaf 19 is arranged to be adjusted vertically by means of an adjusting screw 52 which is screw threaded in a threaded opening 53 extending lengthwise through the leaf flange portion 22 and into the tongue portion 21 of the sight leaf 19. The forward end of the opening 53 opens through the underside of the leaf tongue portion 21 to permit the forward end 54 of the screw 52 to engage the base 13. The forward end 54 of the screw 52, in this instance, is in the form of a square in cross section providing four straight edges 55, adjacent edges being at right angles to each other. The surface 56, of the base 13, engaged by the edges 55 extends forwardly and upwardly from the rear end of the base 13 at an angle to a horizontal line parallel to the lower surface 14 of the base 13. As the screw 52 is rotated the squared end 54 rides up along the inclined surface 56 to raise, or to permit the lowering of, the rear end of the sight leaf 19 (see dotted lines in Figure 4), a quarter turn of the screw 52 being indicated by the dropping of a flat edge against the surface 56. A slot 57 is provided in the outer end of the screw 52 to receive the end of a screw driver for rotating the screw. The sight leaf 19 pivots on the pin 23 and has a sighting notch 58 formed at the approximate center of the upper surface of the leaf flange 22.

The construction of a firearm sight as above disclosed will provide one of rigid structure which is capable of vertical and windage adjustment in an efficient manner. The provision in such a sight of readily formed parts maintains its cost at a minimum. The arrangement of the various parts and of the controlling springs therefore insures positive and accurate adjustment and further insures against loosening of the adjusted parts by the shocks incurred while operating the firearm.

While there has been shown and described herein a preferred form of the invention, it will

be understood that the novel features and principles of this invention may be embodied in other specific forms without departing from the spirit and essential attributes thereof, and it is therefore desired that the present embodiment be considered in all respects as illustrative, and not restrictive, reference being had to the claims rather than to the foregoing description to indicate the scope of the invention.

Having thus fully disclosed the invention, what is claimed as new and for which it is desired to secure Letters Patent, is:

1. In a firearm sight, a base, a leaf, a pin extending transversely across said base and upon which one end of said leaf is hinged, upwardly and outwardly transversely spaced inclined surfaces on said leaf, and a spring pressed plunger carried by said base and engaging each of said inclined surfaces on said leaf to constantly urge said leaf downwardly toward said base.

2. In a firearm sight, a base, a leaf, a pin extending transversely across said base and upon which one end of said leaf is hinged, upwardly and outwardly transversely spaced inclined surfaces on said leaf, and a spring pressed plunger carried by said base and engaging each of said inclined surfaces on said leaf to constantly urge said leaf downwardly toward said base, said leaf hinge pin being screw threaded through said leaf, cooperating means between said base and said pin and including a member adapted to engage the pin and releasably retain it against turning movement, and a spring reacting between said member and one of the plungers to maintain said member in engagement with said pin and the plunger against an inclined surface of the leaf.

3. In a firearm sight, a base having spaced apart side flanges, a leaf having a tongue disposed between said base side flanges, a pin extending between said flanges and being screw threaded to and through said leaf tongue, a member adapted to engage said pin to releasably retain it against turning, an upwardly and outwardly inclined surface on said leaf, a plunger carried by said base and adapted to engage the inclined surface on said leaf to urge the leaf downwardly, and a spring reacting between said member and said plunger to resiliently act against each to press the former against the pin and the latter against the inclined surface.

4. In a firearm sight, a base having spaced apart side flanges, a leaf having a tongue disposed between said base side flanges, a pin extending between said flanges and being screw threaded to and through said leaf tongue, a flat surface on said pin, a member adapted to engage the said flat surface to releasably retain the pin against turning, an upwardly and outwardly inclined surface on said leaf, a plunger carried by said base and adapted to engage the inclined surface on said leaf to urge the leaf downwardly, and a spring reacting between said member and said plunger to resiliently act against each to press the former against the pin and the latter against the inclined surface.

5. In a firearm sight, a base, a leaf, a pin extending transversely across said base and upon which one end of said leaf is hinged, upwardly and outwardly transversely spaced inclined surfaces on said leaf, and a spring pressed plunger carried by said base and engaging each of said inclined surfaces on said leaf to constantly urge said leaf downwardly toward said base, an adjusting screw extending inwardly into said leaf 75 from the rear face thereof, and a forwardly and

upwardly inclined surface on said base in position to be engaged by said adjusting screw to vertically adjust said leaf.

6. In a firearm sight, a base, a leaf, a pin extending transversely across said base and upon which one end of said leaf is hinged, upwardly and outwardly transversely spaced inclined surfaces on said leaf, and a spring pressed plunger carried by said base and engaging each of said inclined surfaces on said leaf to constantly urge said leaf downwardly toward said base, said leaf hinge pin being screw threaded through said leaf to adjust the leaf transversely on the base, a member engaging said hinge pin to releasably retain it against turning, said member having a shank extending crosswise of said base and swingable in respect to the base to pivot the member for swinging movement away from said pin, and a spring reacting between said member and one of said plungers to maintain said member in engagement with said pin and the plunger against the inclined surface of the leaf.

7. A firearm sight including, a base, a leaf, a pin extending transversely of the base and screw threaded through the front end of said leaf to adjust the leaf transversely in respect to the base and upon which the leaf is pivoted for vertical swinging movement, a screw member screw threaded in and extending forwardly from the rear end of said leaf, a forwardly and upwardly inclined surface on said base disposed to be engaged by said screw member to vertically adjust said leaf in respect to said base, and means to resiliently urge said leaf downwardly toward said base.

8. A firearm sight in accordance with claim 7 and in which the pin, upon which the leaf is pivoted, is provided with a flat surface, and a spring pressed member adapted to swing toward and into engagement with the flat surface on said pin to releasably retain it against turning.

9. A firearm sight in accordance with claim 7 and in which the means to resiliently urge said leaf downwardly toward said base includes a spring pressed plunger, and an upwardly and rearwardly inclined surface on said leaf positioned to be engaged by said plunger.

10. A firearm sight in accordance with claim 7 and in which the screw member in said leaf is provided with a square end in engagement with the inclined surface of the base to releasably retain the screw member against turning.

11. A firearm sight including, a base, a leaf, a pin extending transversely of the base and screw threaded through the front end of said leaf to adjust the leaf transversely in respect to the base and upon which the leaf is pivoted for vertical swinging movement, a screw member screw threaded in and extending forwardly from the rear end of said leaf, a forwardly and upwardly

inclined surface on said base disposed to be engaged by said screw member to vertically adjust said leaf in respect to said base, said pin having a flat surface thereon extending crosswise thereof, a member swingably mounted in respect to said base toward and into engagement with the said flat surface to releasably retain the pin against rotation, a plunger slidable in said base toward said leaf, an upwardly and rearwardly inclined surface on said leaf disposed to be engaged by said plunger to urge the leaf downwardly toward said base, and a spring reacting between said swingable member and said plunger to urge the former into engagement with the pin and the latter against the leaf.

12. In a firearm sight, a base, a leaf, a pin extending transversely across said base and upon which an end of said leaf is pivoted, means to constantly urge said leaf downwardly upon said base including, an upwardly and rearwardly inclined surface on the other end of said leaf, and a spring pressed plunger carried by said base and having one of its ends engaging said inclined surface on said leaf.

13. In a firearm sight, a base, a leaf, a pin extending transversely across said base with its intermediate portion extending through and screw threaded to an end of said leaf, said pin having a head portion in engagement with said base, spring means reacting between said base and said leaf to maintain the pin head in close contact with said base and the screw threads in close contact with said leaf, and means to urge the other end of said leaf downwardly toward said base.

14. In a firearm sight, a base, a leaf, a pin extending transversely across said base with its intermediate portion extending through and screw threaded to an end of said leaf, said pin having a head portion in engagement with said base, spring means reacting between said base and said leaf to maintain the pin head portion in close contact with said base and the screw threads in close contact with said leaf, said pin head having a flat surface on its periphery, and a spring pressed member mounted in the base and adapted to engage the flat surface on said pin to releasably hold it against turning in the base and in the leaf, and means to urge the other end of said leaf downwardly toward said base.

GEORGE F. DAVIS.
